Des. 107

C. F. Goodhue and Charles Guild, Cincinnati, Ohio.
Letters Patent, (Design No. 107.) dated 13th January 1849

The schedule referred to in these Letters Patent and making
part of the same.

To all whom it may concern, Be it known, That we David
F. Goodhue and Charles Guild, of the City of Cincinnati, in the
State of Ohio, have invented and produced a new and useful de-
sign for the ornamenting of a cooking-stone; and we do hereby
declare that the following is a full and exact description of the
shape, or configuration thereof, and of the ornaments thereon.

In the accompanying drawing, Fig. 1 is an elevation of

one side of our stove, the other side being similar thereto, Fig. 2, a front, and Fig. 3, a back elevation. Fig. 4, is a top view, showing the hearth plate. In Fig. 1, it is an oven door which is ornamented with a military trophy, consisting of instruments and insignia of war, surmounted by the American Eagle, as represented. The wrought-work moulding, B, B, surrounds the trophy, and the border C, C, the edge of the door. D, is the door leading into the fire chamber, the ornaments upon which are the scrollwork and leafing, E, with the border F. The side plate has the border G, G and the ornaments H, H, and I.

In the front-elevation, Fig. 2, there are two doors, D, D, which are precisely the same with those shown at D, Fig. 1; they are therefore represented in outline only. On each side of these doors are the ends ornaments K.

In the back elevation, Fig. 3, there is a panel having on it the centre ornaments L, surrounded by a border such as shown at M. The wrought-work border G, G, is the same with that so marked in Fig. 1.

On the hearth plate, as shown in the top view, Fig. 4, there is an ornamental border as represented at N, and a centre one as shewn at O.

Having thus fully described and represented the shape and configuration of the respective plates, and delineated the ornaments thereon, what we claim as constituting our new design, and desire to secure by Letters Patent, are the respective plates and doors with the ornaments thereon, as shown in Figs. 1, 2, & 3, and also the particular pattern of the ornaments on the hearth plate, as seen in Fig. 4.
